UNITED STATES PATENT OFFICE

JOHN P. LYNN, OF CHICAGO, ILLINOIS, ASSIGNOR TO DUR-O-LITE PENCIL COMPANY, OF CHICAGO, ILLINOIS, A CORPORATION OF ILLINOIS

PENCIL

Application filed August 1, 1927. Serial No. 209,656.

This invention relates to a mechanical pencil of the type in which a lead propelling mechanism is actuated by rotation of the pencil tip relative to the pencil body; and more particularly it is concerned with a special construction of the tip per se by which it is adapted to contain a reserve supply of leads, and by which the leads are confined in place as long as the tip remains assembled with the body of the pencil.

A suggestive embodiment of this invention is set forth in the accompanying drawing wherein—

Figure 1 is a view in elevation of the pencil in its entirety;

Fig. 2 is an enlarged longitudinal section through the tip and proximate end of the pencil body;

Fig. 3 is a view in elevation of the tip per se;

Fig. 4 is an enlarged transverse section taken on line 4—4 of Fig. 2; and

Fig. 5 is an enlarged fragmentary view, partly in section, showing the tube enlargement which provides a bottom for the magazine within the tip.

The present pencil comprises a body A having an axial chamber 6 which opens out upon the lower end thereof. Associated with this end of the pencil is a tip member B which is frictionally and rotatably connected with the body.

The tip is preferably formed of metal with a head having tapering walls 7 preferably straightened out as at 8, and then inturned at 9 to provide a shoulder which may abut the pencil end. The tip walls which are extended upwardly from this point are of reduced diameter in the form of a body 10 which fits frictionally and rotatably within the chamber 6 of the pencil. At its upper end the walls of the tip are inwardly inclined at 11 and terminate in a sleeve extension 12 which is internally threaded for co-operation with a threaded plunger 14.

Mounted axially within the tip is a tube 15 which is confined in place by the tapered walls at its opposite ends. This tube forms a guide for an active lead C which is adapted to be propelled by the plunger 14 in response

to rotation thereof relative to the tip. The general construction described up to this point has heretofore been known, and no claim thereto is here advanced.

The present invention is concerned with the provision within the tip of a magazine for accommodating reserve leads. As shown, several of such leads D are arranged annularly within the space surrounding the tube 15. The lower ends of these leads may be rested against a shoulder 16 which is formed conveniently by expanding at one point the material forming the tube. This shoulder which extends substantially to the proximate portions of the tip walls 7 forms a bottom for the magazine in which the leads are received. At its upper end this magazine is closed by the tapering walls 11, the leads being confined in place in this region of the tip between its body portion 10 and tube 15. Access to the magazine is afforded by a slot 17 which extends vertically on one side of the tip body 10, the slot also continuing laterally as at 18 in the shoulder portion 9.

When the tip is assembled with the pencil, the slot 17 is closed so as to prevent removal of any reserve lead. By separating the tip from the pencil, however, the slot is uncovered so that the upper end of one of the leads may tilt outwardly through the slot so as to be presented conveniently for grasping. It may then be pulled out by hand, or, if desired, the tip may be inverted to induce removal of the lead by gravity.

In the construction of a tip which fits frictionally and rotatively within a chamber in the lower body end, it is desirable to provide, if possible, some sort of spring action which will assure of a proper connection at all times. This may be best accomplished by slightly bowing from end to end the walls of the tip body 10, and providing therein one or more slits to leave intervening spring sections which will bear frictionally against the walls of the pencil body. In the present invention the slot 17 which is the door to the magazine serves admirably to permit of such spring action, so that the tip is assured at all times of a desirable connection with the body of the pencil.

I claim:

1. A pencil having a body with an axial chamber open at its lower end, and a tip applied to said end of the body, the tip being provided with a body portion which is extended into the chamber of the pencil body for frictional connection therewith, the tip being hollow and having in its body portion a slot extending longitudinally of the pencil through which reserve leads may be passed into or out of the tip, the slot being closed when the tip is assembled with the pencil body, substantially as described. 70
2. A pencil in which is combined a body having an axial chamber open at its lower end, a tip having a portion receivable within the chamber to frictionally engage the walls surrounding the same, there being a slot formed longitudinally through the walls of said portion adapted to be wholly closed by the body walls when the tip is assembled with the body, and a tube arranged axially within the tip in spaced relation to the walls thereof providing an annular chamber wherein reserve leads may be accommodated, the leads being removable through the slot only when the tip is separated from the body of the pencil, substantially as described. 80
3. A pencil in which is combined a body having a chamber open at the lower end thereof, and a hollow tip formed with walls which extend in part within the chamber for frictional connection therewith, the tip being provided with a central tube in spaced relation to its walls whereby there is formed an annular chamber within the tip, a portion of the tube being laterally expanded at one point to form a bottom for the magazine within the tip, there being provided in the walls of the tip which are engaged by the pencil body a slot through which a reserve lead may pass, the slot being wholly covered when the tip is assembled with the pencil, substantially as described. 90
4. A pencil in which is combined a body having a chamber open at its lower end, a hollow tip receivable in part within the chamber for connection with the pencil body, a tube arranged axially within the tip in spaced relation to the surrounding walls thereof, the space between the tube and tip being closed at both ends whereby to provide a magazine for reserve leads, there being a slot formed longitudinally through the walls of the tip between the ends thereof affording access to the magazine interiorly of the latter, the slot being so located as to be covered by the walls of the pencil body when the tip is assembled therewith, substantially as described. 100
5. In a pencil comprising a barrel, a removable tip therefor including a tapered end and a reduced sleeve portion extending into the barrel in telescopic engagement therewith, and lead-propelling means including a plunger disposed axially in said sleeve and movable longitudinally therein and removable with said sleeve and tapered tip from the barrel, said sleeve being dimensioned to provide an annular spare lead magazine around the plunger. 105
6. In a mechanical pencil, a barrel and a removable tip telescopically engaged therewith, said tip containing a magazine for spare leads, and lead-propelling mechanism carried by the tip and removable from the barrel therewith. 115
